UNITED STATES PATENT OFFICE.

DAVID HALLOCK, OF NEW YORK, N. Y.

WEIGHING-SCALE.

SPECIFICATION forming part of Letters Patent No. 311,745, dated February 3, 1885.

Application filed July 14, 1883. (No model.)

To all whom it may concern:

Be it known that I, DAVID HALLOCK, of the city and county of New York, in the State of New York, have invented a new and useful Improvement in Scales, of which the following is a specification.

My invention relates to a scale in which several weights are held on a fixed support, from which they are raised automatically and 10 successively by the upward movement of the jack produced by placing the commodity to be weighed on the scale; and it consists in various novel combinations of parts and details of construction hereinafter described, and set 15 forth in the claims.

In the accompanying drawings, Figure 1 is a side elevation of a scale embodying my invention, the weight-case, weights, and appurtenances being shown in section. Fig. 2 is a 20 plan of the scale, including a horizontal section of the weight-case and a hood which covers the weights. Fig. 3 is a vertical section and a partial section of the weights in a plane transverse to the length of the scale-beam. Fig. 4 is an elevation of the weight-support employed. Fig. 5 is an elevation of 25 the end of the scale, and Fig. 6 is a detail sectional view of the beam, its bearings, and parts of the jacks.

Similar letters of reference designate corresponding parts in all the figures.

A designates the scale-beam, here shown as consisting of an open frame provided with the knife-edge pivots a , which rest in bearings a' 35 in the top of a post or standard, B, projecting upward from the base B'. The bearings a' are covered by caps a^2 , which preclude the pivots from being removed entirely from the bearings until the caps are taken off.

On the top of the beam A, and directly over the pivots a , are projections a^2 , and above the projections and on the under side of cap a^2 are concave recesses a^4 , (see Figs. 1 and 6,) adapted to receive such projections when the beam is wedged up, so as to raise the pivots a off their bearings.

At the two ends of the beam A are knife-edge pivots b c , upon which the jacks C D are respectively supported, the jacks being constructed with bearings b' c' , which are above and rest upon the pivots b c . Immediately

below the beam the jacks C D are respectively provided with cross-pieces or stretchers C' D', and on the under side of the beam are recesses b^2 c^2 .

In packing scales for transportation it is usual to wedge or block up the jacks, so as to remove the pivots a b c from contact with their bearings; but this does not commonly prevent the beam from moving lengthwise, 60 and so bringing the said pivots in contact with the sides of said bearings.

In my scale, when the jacks are wedged or blocked up to prepare the scale for transportation, the cross-bars or stretchers C' D' are 65 brought up into the concave recesses b^2 c^2 , as shown in Fig. 6, and the jacks are thus locked against a movement lengthwise of the beam, and the projections a^2 are brought up into the concave recesses a^4 , and the beam is thus locked 70 against longitudinal movement. Therefore the pivots are kept out of contact with the sides of their bearings, as well as the portions on which they normally bear, and hence are preserved from injury.

Upon the jack C is supported the scale-pan E or the platform for articles to be weighed, and the jack D acts upon the weight at the opposite end of the beam.

To the lower portion of the jack D is loosely 80 pivoted a swinging check or guide, O, whereby the jack is maintained in a vertical position as it is raised and lowered, and the weights are prevented from rubbing against the support, which would produce friction.

The weight-case is formed in two sections, F F', one of which, F, is attached permanently to the base B', while the other, F', is detachably secured in place, and may be removed, when desired, to afford access to the interior 90 of the weight-scale.

G designates the indicator, which has knife-edge pivots d resting in a bearing, e , projecting from the portion F of the weight-case. The indicator extends through a slot in the top of the weight-case, and ranges over a dial, G', to indicate the number of pounds weight of the article in the pan. The indicator G is formed with a curved arm, G², extending from a point just above the pivot d around under the bearing e , and having a pin-and-slot connection, c' , or other loose connection with the

100

jack D. This construction is very advantageous, because the curved arm G² will bear upon the bottom of the bearing e, and so prevent the indicator from being raised sufficiently to detach the pivots d from the bearings e. This construction prevents the indicator from being accidentally dismounted during transportation or rough usage.

The weights in all cases for use with this scale are arranged in a vertical tier and about a common center, and they are adapted to be raised or lifted successively by the jack D.

As here represented, the weights consist of flat plates H H' H² H³, which are of equal or unequal weights. They may, for example, when resting on the jack, each balance a pound weight in the pan.

I designates the support for the weights, which is formed upon a bracket secured to the portion F of the weight-case. The ends and sides of this support converge upward, as best shown in Figs. 1 and 4, and the ends are of stepped construction, as shown in Figs. 3 and 4, having bearing-surfaces f f' f² f³.

The weights, of which any number may be used, are provided or furnished with apertures or slots g g' g² g³, which conform in shape to the support, the aperture g in the lowest plate, H, being of a size to pass downward over the support until it reaches the step or bearing f, the next plate, H', having its aperture g' of such size that it will pass downward over the support I until it rests on the step or bearing f', and so on, the weights being supported above and out of contact with one another in a vertical tier and about a common center.

In the back of the aperture in each weight is a recess or notch, h, and on the back of the support is a vertical rib, h', which is received in the notches, but is sufficiently smaller than the notches to prevent the weights from binding on this rib as they rise and fall. This rib and the notches form a guard for preventing the shifting of the weights laterally to such an extent that they will, when moving downward, stop upon any step or bearing above the proper one. In lieu of this guard, a guard or guide of any other construction may be used.

As shown in Figs. 3 and 4, the surfaces i at the ends of the support I between the steps or bearings f f' f² f³ are inclined, while the edges of the apertures g g' g² g³ are or may be straight. It will also be seen from Fig. 1 that the sides of the support I are inclined; consequently as the weights are lifted they are carried away from the inclines, and the spaces on all sides between the supports and weights increase, and there is no liability of the weights rubbing on the support, and thus impairing the accuracy of the scale. The support I, as here constructed, affords clearance to the weights on all sides, and in falling back the weights are guided in every direction.

J designates a hood which covers the weights and prevents dirt or dust from accumulating on them, and so impairing to a certain extent the accuracy of the scale, and also to prevent

particles from lodging between or on the weights or on the bearings, so as to interfere with the correct movement and action of the weights and scale. The hood J is imperforate, and is supported in a fixed position immediately over the weights. It will therefore be very effective in protecting the weights. As here shown, the hood rests upon and is secured to the top of the support I, and extends down behind the weights, as shown in Fig. 1. The back of this hood is shown as beveled at j, so that if the weights strike against it in going up they will not bind, but will fall away. The part J not only serves as a hood, but the weights are of such thickness and the part J is secured at such a distance above the step f³ of the support I that the hood will prevent any one of the weights from passing and catching upon the step of the support corresponding to the next weight, even if the scale be turned upside down, as it might be in transportation. For example, the hood J will prevent the weight H² from passing beyond or above the step f³ and lodging thereon. The hood J therefore forms a guard to prevent derangement of the weights on the support. As is best shown in Fig. 3, the jack D straddles or extends beyond the base of the support I at each end, and acts upon the lowermost weight, H, near its ends, and hence the weight falls equally on opposite sides of the longitudinal center of the beam, and the two or more points of contact of the jack and weight being so far apart, giving a broad base, there is little or no liability or tendency for the beam or weight to cant or tilt. When weight is placed in the pan, the jack D rises and first picks up the lowermost weight, H, next the weight H picks up weight H', and so on until all the weights have been raised, each weight raising and supporting the weight next above it. The upwardly-projecting ends of the jack D are plain flat surfaces and bear on plain surfaces on the lowermost weight, and hence any side or lateral movement of the jack may take place without crowding the weights against the support, as the jack will be free to so move without imparting such side movement to the weights. This is important, as in carelessly placing goods in the scale-pan the beam and jack are liable to be shifted laterally more or less.

It will be observed that the under side of each weight is on the same plane as the step or bearing f or f', &c., on which it rests, and hence the lifting-point of the weight is on the same plane with its support. If the lifting-point is at a distance above or below the supporting-point, there is liability, especially when the scale is worn, of the weights tilting and rubbing on the support, thereby creating friction, which impairs the accuracy of the scale.

The several weights H H', &c., are only capable of weighing fixed amounts automatically, and to provide for indicating weights intermediate between those indicated by the weights H H', &c., I attach to the beam A a supple-

mental graduated beam or bar, S, upon which a weight, S', may be shifted horizontally to indicate the intermediate weights.

From the above description it will be observed that in my scale the weights are held one above the other on a fixed support, from which they are raised automatically and successively by the upward movement of the jack produced by placing on the scale a commodity to be weighed. Such a scale is radically different from one in which the weights are arranged on a movable support, which must be lowered by a manual operation before weighing, to deposit one or more of the weights upon the jack.

What I claim as my invention, and desire to secure by Letters Patent, is—

1. The combination, with a scale-beam and its jack, of a number of weights and a fixed support comprising steps for retaining them one over the other with their centers of gravity all on the same vertical line, and also comprising inclines above the steps, substantially as and for the purpose described.

2. The combination, with a scale-beam and its jack, of a number of weights adapted to be lifted successively by an upward movement of said jack, and a fixed support for said weights, the points of supports of the weights and the points acted on in raising them being in approximately the same planes, and the weights or support being beveled or inclined on all sides to guide the weights in all directions as they fall back to their proper position, and to afford an increasing space on all sides between the weights and support as the weights are lifted, substantially as described.

3. The combination, with a scale-beam and its jack, of a vertical tier of weights adapted to be lifted successively by an upward movement of said jack, and a fixed support for the weights, the weights or support being beveled or inclined on all sides to guide the weights in all directions as they fall back to their proper positions on the fixed support, and to afford an increasing space on all sides between the weights and support as the weights are lifted by the jack, and the lowermost weight having a plain surface acted upon by plain surfaces on the jack to allow the jack to move laterally without so moving the weight and crowding it against the support, substantially as described.

4. The combination, with a scale-beam and a jack, of a vertical tier of weights capable of being raised successively by an upward movement of the jack, a fixed support for the weights, the said beam having a graduated bar, and a weight movable on said bar for indicating weights intermediate between those indicated by the weights of the series, substantially as described.

5. The combination, with a scale-beam and its jack, of a vertical tier of weights adapted

to be lifted successively by the upward movement of the jack, and a fixed support comprising steps for the weights and inclines above the steps, whereby the weights in rising move away from the inclines, substantially as herein described.

6. The combination, with a scale-beam and a vertical tier of weights adapted to be lifted successively, of a jack on the beam adapted to act upon the lowermost weight near its ends, and to raise the weights successively by its upward movement, and a fixed support for the weights between the two bearing-points of the jack, substantially as and for the purpose described.

7. The combination, with a scale-beam, of a fixed stepped support, a vertical tier of weights, the several weights having apertures of different sizes adapted to the several steps of the support, and a jack adapted to act upon the lowermost weight and to raise the weights successively by its upward movement, substantially as herein described.

8. The combination, with the scale-beam and its jack, of the stepped support I, provided with a rib, h', and weights H H', &c., having apertures of different sizes, and notches h, substantially as described.

9. The combination, with the scale-beam, of a number of weights to be lifted successively, an indicator having knife-edge pivots and bearing, and a curved arm extending from the indicator around under said bearing and connected with said jack, substantially as described.

10. The combination, with the scale-beam and its jack, of a number of weights to be successively lifted by the jack, the support comprising steps for the weights, and on which they are placed from the top thereof, and a hood independent of and within the case of the scale, placed immediately above the support and serving to protect the weights and to hold them in their proper positions on the stepped support, substantially as herein described.

11. The combination, with the scale-beam having pivots a b c, and having recesses b' c' in its under side and projections a' on its upper side, of the caps a", having concave recesses a', adapted to receive said projections, and the jacks having bearings for the pivots b c, and provided with portions adapted to engage with the recesses b' c' of the beam for the purpose of providing for locking all the parts in such manner as to keep the pivots securely out of contact with their bearings when the scale is packed, substantially as herein described.

DAVID HALLOCK.
